CORNER MARKER FOR LAND SURVEYS

Filed March 11, 1927

4 Inventor
George A. Cromie
Seymour Pearce Nichols
Attest

UNITED STATES PATENT OFFICE.

GEORGE A. CROMIE, OF NEW HAVEN, CONNECTICUT.

CORNER MARKER FOR LAND SURVEYS.

Application filed March 11, 1927. Serial No. 174,552.

My invention relates to an improved corner marker for land surveys, the object being to provide a simple, durable, conveniently-installed marker constructed with particular reference to weather-resistance, visibility and adaptability to be so anchored as to resist removal by the careless or malicious, whereby the permanence of land surveys is secured to a degree not before possible, save at prohibitory expense.

With these ends in view, my invention consists in a corner marker having certain details of construction as will be hereinafter described and pointed out in the claim.

15 In the accompanying drawings:

Fig. 1 is a view in perspective of a corner marker constructed in accordance with my invention;

Fig. 2 is a view showing the same as installed so as to form what is known by surveyors as a "monument";

Fig. 3 is another form of my corner marker provided in this instance with a shield-shaped location-head and with a cast-cement base; 25 and

Fig. 4 is a broken view of the upper end of a rod of a marker provided with an integral location-head.

In carrying out my invention as shown 30 in Figs. 1 and 2, the marker consists of an upright rod 5 preferably made of a superior grade of Swedish iron known for its quality of resisting weather, bent at its lower end to form a substantially-circular anchor 35 6 located in a plane at a right angle to the vertical plane of the rod, though it is not essential that this anchor should be substantially circular in form, the only requirement being that it shall lie in a horizontal plane 40 and be fitted to be held down by a superimposed load of stones, gravel, or dirt. At its upper end, the rod 5 is provided with a disk-like location-head 7 secured to it by a rivet 8, or in any other approved manner, the 45 upper face of this head being provided with lettering or figures (not shown), or other indicia of ownership and relative location, either cast or cut into it or etched or painted upon it, as may be found convenient.

50 In Fig. 2 I have illustrated a mode of installation consisting in digging a hole 9 on the bottom of which the anchor 6 rests. Small stones 10 are then piled upon the an-

chor and about the lower end of the rod, around the upper portion of which stones 55 11 are piled, the extreme upper end of the rod, with its location-head 7, rising above them. It will be clear that when so installed, the marker cannot be removed, save by considerable effort and is likely to be left 60 undisturbed.

In the form of marker shown by Fig. 3, the upper end of the rod 5 is furnished with a shield-shaped location-head 12 permanently secured by a rivet 13 or otherwise and located in the vertical plane. This location-head will be provided with initials or figures according to circumstances and secures a high degree of visibility, particularly when galvanized. In this construction, the anchor 6, 70 at the lower end of the rod, has cast upon it a heavy base 14 of concrete, which secures additional permanence of installation at somewhat greater expense. The corner marker shown by Fig. 3 is designed to be installed in the same manner as illustrated in Fig. 2.

In Fig. 4 the rod or post 5 is flattened to form an integral location-head 15 of smaller area than the location-heads 7 or 12 and having, therefore, less visibility but answering all purposes and, being integral with the rod, impossible to remove therefrom and also cheaper to produce.

By preference, the rod and location-head 85 will be galvanized for increasing their visibility and, to some extent, their resistance to weather, though this is not considered essential.

By means of my improved corner marker, 90 the land-owner, who has gone to the expense of a survey of his holding, whatever its size and character, may give permanence to his established lines, making further surveys comparatively easy and largely eliminating 95 the boundary disputes so vexatious to all land-owners.

I claim:

As a new article of manufacture, a self-contained corner-marker for land-surveys, 100 comprising a metal rod, a location-head made independent of the said rod, permanently attached to the upper end thereof and overhanging the same so as to show a relatively-large display-surface, an anchor formed integral with the lower end of the rod, arranged 105

in a plane at a right angle thereto and substantially concentric therewith and comprising an arm bent at a right angle to the lower end of the rod and having a circular extension, and a cement base initially cast around the said anchor which is embedded in it and standing in a plane at a right angle

to the plane of the rod, whereby, when a load is imposed upon such base, the rod is maintained in a vertical position.

In testimony whereof, I have signed this specification.

GEORGE A. CROMIE.
